UNITED STATES PATENT OFFICE.

WILLIAM K. B. SWINT, OF PHILADELPHIA, PENNSYLVANIA.

DESIGN FOR A GAME-BOARD.

56,543.

Specification for Design.

Patented Nov. 2, 1920.

Application filed May 25, 1920. Serial No. 384,161. Term of patent 14 years.

To all whom it may concern:

Be it known that I, WILLIAM K. B. SWINT, a citizen of the United States, residing in Philadelphia, Pennsylvania, have invented a certain new, original, and ornamental Design for a Game-Board, of which the following is a specification.

My design for a game board is clearly illustrated in the accompanying drawing, which represents a face view of the game board.

The dominant features of this design are the graphic representation of a clock and a track or raceway associated with the clock and extending upwardly and downwardly at the sides thereof.

I claim:

The ornamental design for a game board as shown and described.

WILLIAM K. B. SWINT.
